UNITED STATES PATENT OFFICE.

CHARLES KARL KOVALCHIK, OF BRADLEY, OHIO.

CARBIDE LAMP.

Application filed April 15, 1925. Serial No. 23,210.

To all whom it may concern:

Be it known that I, CHARLES K. KOVALCHIK, a citizen of Austria-Hungary, residing at Bradley, in the county of Jefferson 5 and State of Ohio, have invented certain new and useful Improvements in Carbide Lamps, of which the following is a specification.

This invention has reference to miners' 10 carbide lamps and more particularly to certain novel improvements in the lamp structure whereby the employment of a threaded joint between the water reservoir and the lamp bottom is dispensed with in favor of a 15 non-threaded joint presenting certain practical advantages over the threaded type of joint.

With the above in view, the invention provides a novel form of clamp consisting of a 20 locking ring on the water reservoir capable of expansion and contraction and adapted to be contracted about a retaining rim on the lamp bottom, thereby enabling the lamp parts to be readily connected or disconnected 25 whenever desired and without any tendency of the lamp parts to bind or stick at the joint.

A further object of the invention is to provide sealing means for making the joint 30 gas-tight and in so arranging the sealing means on the bottom of the reservoir that it will always be correctly positioned for proper engagement with the retaining rim of the lamp bottom.

35 A still further object is to provide a carbide lamp in which the bottom of the water reservoir is formed with a suitable pocket to receive packing and in providing novel means for holding the packing in place.

40 Other objects and advantages of the invention may be apparent from the following description and from the accompanying drawing of the invention, wherein

Figure 1 is a side elevation of a miner's 45 carbide lamp constructed in accordance with the invention,

Figure 2 is a side view of the lamp partly in elevation and partly in section to illustrate the interior construction thereof,

50 Figure 3 is a bottom plan view of the lamp, on an enlarged scale, and

Figure 4 is an enlarged sectional view, the section being taken on line 4-4 of Fig. 2.

Describing the invention in detail, 10 designates the upper part or body of the lamp 55 having the usual water chamber 11 provided

with a filling opening normally closed by the cap 12. At one end of the body is a hook 13 for attaching the lamp to a miner's cap and at the other end is a reflector 14. 60 The water in chamber 11 is conducted to the lower part or carbide-container 15 of the lamp through a drip-pipe 16 having the usual valve means (not shown) operated by the valve-rod 17 for regulating and controlling the discharge. The gas generated in the carbide chamber 18 is conducted upwardly in the usual manner by a gas tube 19 leading to the burner 20 at the center of the reflector. 70

It has, heretofore, been the practice to connect the lamp body 10 and the lamp bottom 15 by screw-threaded engagement. Such a connection, however, has many disadvantages, one of the most common of which is the tendency of the threads to bind and lock the parts together so as to make them practically inseparable. Such binding may result from the corroding of the threads from the damp atmosphere of the mines or from the accumulation of carbide between the threads forming a binding cement, or from other causes. It is the purpose of the present invention to do away with the threaded connection and to substitute therefor a 75

clamping connection such as hereinafter described. In substituting the threadless joint of the present invention for the aforesaid screw threads, the body 10 of the lamp is equipped with a flexible and resilient locking ring which can be expanded and contracted and the lamp bottom or carbide container 15 is provided with a retaining rim about which the said locking ring is adapted to be contracted for clamping and locking 80 the top and bottom parts of the lamp securely together, means being provided for operating the locking ring to connect or release the lamp parts, as desired. 95

The locking ring may be formed of an 100 annular metal band 21 encircling the body 11 adjacent its lower end and secured thereto in any suitable manner. Integral with the band and depending below the lower end 105 of the body is a circular series of flexible gripping fingers 22, each of which terminates in an eye 23. These fingers are spaced laterally from each other so as to be freely movable without interference from one another when flexed inwardly and outwardly by the contraction and expansion of the wire loop 24. This wire loop extends completely 110

around the locking ring, passing through the eye 23 of each finger 22 and having its free ends extending outwardly of the ring at a common point and terminating in relatively oppositely disposed hooks 25-25'. A conventional type of clamp 26 is engaged with the hooks 25-25' in the manner shown and operates to draw the ends of the loop together, for contracting the ring, when pushed from a horizontal to a vertical position. When the clamp extends horizontally, as seen in Fig. 3, the hooks 25-25' are free to spread apart and thus allow the locking ring to expand. The retaining rim of the container 15, about which the locking ring is adapted to be clamped, may be formed by rolling the upper edge of the container to provide a bead 27, or it may be formed in any other manner desired, the essential point being that the wire loop, and hence the gripping fingers 22, are contracted to engage the sides of the container immediately below the bead, thus providing a secure and firm connection. The metal band 21 and fingers 22 may be formed of some material which is merely flexible, such as tin, and the wire loop 24 of spring wire. However, the entire locking ring may be made of resilient metal, if so desired.

The bottom of body 10 has a recess or pocket 28 in which is placed a packing 29 of felt. This felt packing is retained in place by a holder consisting of a disc 30 of such diameter as to snugly fit within pocket 28 and being suitably apertured to fit over the lower ends of the water tube 16 and gas tube 19. The holder is secured in position by two springs 31-31' fastened to the underside thereof on respectively opposite sides of the central aperture, as shown in Fig. 4, and so flexed as to normally press inwardly against the side of the water tube. Depending from the outer edge or rim of the pocket 28 is a circular flange 32. This flange, in conjunction with the metal band 21, provides a channel adjacent the outer edge of the bottom of the body 10 and so positioned as to lie above the bead 27 of the container 15. Within the channel thus formed is positioned a rubber gasket 33. Consequently, when the lamp parts are assembled, the gasket rests directly upon the

bead 27 and thus seals the joint, thereby making the connection absolutely gas-tight.

From the foregoing it will be obvious that the formation of the pocket 28 and gasket-receiving channel in the bottom of the water reservoir 10 enables the packing and gasket to be readily renewed whenever desired, and the provision of the locking ring enables the lamp bottom to be securely connected or disconnected to the water reservoir without danger of binding. By the mere manipulation of the clamp 26, the locking ring is readily adjusted to lock the parts together or to permit their prompt separation.

Having thus described the invention, what I claim is:

1. In a carbide lamp, a water chamber having a plurality of flexible gripping fingers, a carbide-container having a retaining rim adapted to be engaged by the said gripping fingers, and means for contracting the said fingers about the said rim to securely lock the container to the said water chamber.

2. In a carbide lamp, a lamp body constituting a water reservoir, a plurality of flexible gripping fingers depending below the lower end of the said body and respectively terminating in an eye, a carbide-container having a retaining rim adapted to be engaged by the said gripping fingers, a spring loop encircling the said gripping fingers and being supported in the eye of each finger, and means for expanding and contracting the said loop.

3. In a carbide lamp, a carbide chamber presenting a retaining bead, a water chamber above the carbide chamber, an annular metal band encircling the said water chamber adjacent its lower end and suitably secured thereto, said band having a plurality of integrally formed flexible gripping fingers depending below the lower end of the water chamber for engaging over the retaining bead of the said carbide chamber and being capable of contraction and expansion, and operating means associated with the said depending fingers for contracting the same into locking engagement with the said retaining bead.

In testimony whereof I affix my signature.
CHARLES KARL KOVALCHIK.
